UNITED STATES PATENT OFFICE.

ERASTUS ALDERSON, OF NORTH YAKIMA, WASHINGTON.

ANVIL-VISE.

No. 874,722.

Specification of Letters Patent.

Patented Dec. 24, 1907.

Application filed March 22, 1907. Serial No. 363,852.

To all whom it may concern:

Be it known that I, ERASTUS ALDERSON, a citizen of the United States, residing at North Yakima, in the county of Yakima and State of Washington, have invented a new and useful Anvil-Vise, of which the following is a specification.

This invention relates to compound tools of the type known as anvil vises and used especially by blacksmiths for clamping and holding small articles against an anvil while working on them.

The object of this invention is to provide an anvil of the usual type with a clamping or vise jaw on its rear side and operated by the foot to hold an article firmly against the anvil on which he may be working, and thus leave both his hands free for the use of tools.

The principal use however for which this invention was designed is to hold horse shoes while the calks are being sharpened, and to this end the invention comprises certain combination and arrangement of parts, to be hereinafter described and claimed.

In the accompanying drawings: Figure 1 is a perspective view of the anvil vise complete. Fig. 2 is a detail view in perspective of the bearing plate. Fig. 3 is a perspective view of the vise jaw as seen from its inner side.

Similar numerals indicate the same parts in all the figures.

On one end of the usual upright wooden block 1 is an anvil 2 secured in place thereon by the usual means 3. The anvil being of ordinary construction and without alteration or change from those in common use, a detailed description is deemed unnecessary. On one side of the block, by preference the right hand side as one stands in front of the anvil, is a substantially horizontally disposed bearing 4 comprising a bar 5 and a downwardly extending arm 6, the bearing in fact being T-shaped. Bolts 7 fasten said plate 4 to the block which may be recessed to permit the plate lying flush with the block. Pivot ed to the plate 4 by a bolt 8 is a swinging lever 9 carrying at its upper end a vise jaw 10, the inner face 11 of which is roughened or grooved as shown to prevent all articles held by the vise jaw from slipping. Journaled on the downwardly projecting arm 6 of the bearing 4 by a bolt 12 is a foot lever 13 ex-

tending across the base block from front to rear and having a bifurcated boss or head 55 upon its rear end and a treadle 15 on its front end. A link 16 is pivoted between the two parts of the boss or head 14 by a pin 17 and to the vise lever 9 by a similar pin 18. A recess 19 is made in one side of the vise lever to 60 admit the head 20 on the upper end of the link 16 which head bears on a boss or lug 21 extending rearwardly from said link on the opposite side and through which the pin 18 passes.

A vertical plate 22 is fastened to the front side of the block 1 near the ground and has on its exposed edge ratchet teeth as shown, to engage a tooth 23 projecting laterally from the inside of the foot lever 13. 70

In the operation of the invention which is easily understood, some article, say a horse shoe is placed by a blacksmith between the rear of the anvil and the head or jaw 10 of the vise. Now by placing the foot on the 75 treadle 15 the foot lever 13 is rocked on its pivot, lifting the rear end, which, through the link 16, swings the vise lever 9, carrying the jaw 10, against the horse shoe holding it firmly in position to be operated on. The 80 tooth 23 on the foot lever 13 engages one of the ratchet teeth 22 and holds said foot lever depressed and the vise jaw tightly closed until the blacksmith, by a side movement on the treadle, disengages the tooth from the 85 ratchet.

Having thus described the invention what is claimed is:—

In combination, an anvil block, an anvil mounted thereon and secured thereto, a T- 90 shaped bearing bolted to said block, a vise lever, pivoted to said bearing, a foot lever also pivoted to said bearing, a connecting link between the rear end of the foot lever and the upper end of the vise lever, and a 95 ratchet plate attached to said block adapted to engage said foot lever and hold the vise jaw against the anvil.

In testimony that I claim the foregoing as my own, I have hereto affixed my signature 100 in the presence of two witnesses.

ERASTUS ALDERSON.
